WALTER L. COOKE, OF CLEVELAND, OHIO, ASSIGNOR TO THE NATIONAL PAINT & VARNISH COMPANY, OF CLEVELAND, OHIO, A CORPORATION OF OHIO.

AGITATOR FOR PAINT IN BARRELS.

No. 927,952.

Specification of Letters Patent.

Patented July 13, 1909.

Application filed October 24, 1908. Serial No. 459,342.

To all whom it may concern:

Be it known that I, WALTER L. COOKE, a citizen of the United States, residing at Cleveland, in the county of Cuyahoga and 5 State of Ohio, have invented a certain new and useful Improvement in Agitators for Paint in Barrels, of which the following is a full, clear, and exact description, reference being had to the accompanying drawings.

10 This invention relates to devices for agitating paints and similar substances in barrels or other containing vessels, the object being to provide a device for accomplishing this purpose which shall be cheap in construction and efficient in operation, and 15 which shall be assembled with the containing vessel so as to be always in position and ready for use.

In the accompanying drawings forming a 20 part of this application, Figure 1 is a longitudinal section through the center of a barrel having my agitator therein, the same being ready for use; the agitating device being shown in broken lines in position at right 25 angles to the position shown in full lines; Fig. 2 is a similar section through the upper part of the barrel showing a portion of the agitator and the crank for operating the same, the crank being secured to the barrel 30 head ready for shipment or storage; Fig. 3 is a perspective view of the crank for turning the agitator; and Fig. 4 is a section through the crank-lever and the handle therefor showing the relation of these parts when 35 prepared for shipment or storage, said figure being taken substantially on the line 4—4 of Fig. 2; Fig. 5 is a top plan view of the agitating device.

As is well understood, paints, and some 40 other substances, when standing for some time tend to separate, the heavier particles or ingredients of the paints settling to the bottom, making it necessary to agitate the paint thoroughly so as to obtain a uniform 45 mixture before it is fit for use. When the paints are confined in barrels, it is very difficult to adequately agitate the paint owing to the weight of the barrel. Consequently, the ingredients of paints which are drawn 50 from a barrel are liable to be out of proper proportion, the paint first drawn from the barrel being too thick and the remainder too thin. The device hereinafter described is intended to thoroughly agitate and stir 55 the paints in the barrel so that paint

drawn therefrom at all times will have substantially the same proportion of ingredients.

Taking up a description of the invention by the use of reference characters, 1 represents a barrel of any size, the same having the bottom head 2, and the top head 3. Secured to the inner side of the head 2 at its center is a plate 4, the same forming the lower journal for the central vertical shaft or axle 5 of the agitator. The top head 3 is provided with a central aperture containing a suitable bushing or packing 6, into which aperture the upper end of the shaft 5 projects so as to be engaged by the angular 60 socketed portion 7 of the crank 8. The shaft 5 has a loose connection with the member 8 so that it may occupy a position in the socket 7 at any place between the top and bottom thereof. This feature allows the 65 adjustment of my device to accommodate slight variations in the heights of barrels. The crank is turned by means of a hand grip consisting of a sleeve 9 and a pin or bolt 10 upon which the sleeve is journaled, the lower 70 end of the bolt being screwed or otherwise removably secured to the outer end of the crank 8. The lower side of the crank is recessed at 11 so as to adapt the same for receiving the sleeve 9 and bolt 10, which may 75 be removed from the end of the crank and placed in said recess, after which the crank is secured to the head 3 by screws 12 and 13, which are respectively passed through the outer end of the crank and through a flange 80 14 extending from the hub of the latter. The purpose of this construction is to take 85 care of the handle and get it out of the way during shipment or storing. As shown in Fig. 3, a plurality of holes may be formed in the same flange so as to receive a sufficient number of screws for holding the crank securely in place during the shipment of the barrel, the packing 6 being sufficiently tight 90 to prevent leakage of the paint.

Secured to the shaft or axle 5 at the lower 95 end thereof is a bar 15 which extends at right angles to the said shaft 5. A second bar 16 is likewise secured to the shaft 5 at a point above the bar 15 and at substantially the 100 middle part of the agitating device. The said bar 16 likewise extends at right angles to the axle 5 and moreover extends in a direction at right angles to the direction of the bar 15. Steel blades 17 are secured at one of 105 110

their ends to the opposite ends of the bar 15, and at substantially their central portions are secured to the opposite ends of the bar 16 and at their upper portions are secured to the 5 shaft 5. The members 17 are formed of steel and in their original shape, before being bent to the position shown in the drawing, are prepared by subjecting a flat strip to a rolling operation along one edge thereof, 10 which will lengthen the said edge and cause the bar to assume a rounded shape in a horizontal plane. A strip thus treated, when bent and mounted as shown in the drawings, will always present the edge of the strip or 15 blade to the material it contacts, thereby cutting through the said material, while at the same time the lower portion of the blades will get under the thick paint and turn it over, the action being similar to that of a 20 plow-share. This arrangement is found very desirable for, as is well known, the material which will collect at the lower part of the paint barrel will be quite heavy, and in fact may become substantially solid, and therefore 25 in order to cause the agitating device to move through this material, it is necessary to present to the material a cutting edge, otherwise the resistance to the movement of the agitating device would be sufficient to make 30 it inoperative. The lower portion of the blades are bent at points 17^a, below which points the blades are flat and slant upwardly. These portions of the blades will raise the 35 material with which it contacts. The portions of the blade to the rear of the cutting edge are shaped and arranged at a proper angle to the edge so as to elevate the material through which the forward edge of the blade has penetrated. This construction nearly 40 resembles a side of a plow share blade.

Above the bar 16 the members 17 are so shaped as to gradually present a more flat surface to the material with which it comes in contact during its rotation. The purpose 45 of this is to thoroughly agitate and set in motion the light material, which is usually a liquid, at the upper part of the barrel which offers little or no resistance, causing it to descend along the sides and gradually to work 50 into the heavy material at the bottom of the barrel. Thus by lifting the heavy material at the bottom of the barrel and causing the lighter material to come into contact therewith, the whole mass is thoroughly mixed.

55 The lower cross arm to which the lower ends of the blades are secured is mounted so as to carry the blades near the bottom of the barrel and also near the spigot 18. The arms 15 and 16 may be secured to the shaft or axle 60 5 in any suitable way, and the arms may be flat bars, or they may be angle irons, as desired.

When a barrel of paint is received, the crank 8 is removed, and the sleeve 9 and the 65 bolt 10 forming the hand-grip are fixed to the

crank, after which the same is applied to the opening in the upper barrel head, and to the shaft 5, which is preferably squared, as shown in Fig. 3.

Various changes in the details of the construction shown may be made without departing from the spirit of my invention, and the following claims are not intended to be limited to such details any further than is rendered necessary by the terms therein employed. 75

Having thus described my invention, what I claim is:

1. The combination, with a barrel, an agitator therein comprising a central shaft, cross 80 arms thereon at different elevations and extending in different directions, and blades secured at their upper ends directly to the shaft and extending in a twist across and secured each to a plurality of cross arms. 85

2. The combination with a barrel, of an agitator therefor comprising a central shaft and spiral members carried thereby and acting like a plow-share on the contents.

3. In an agitator, the combination of a 90 shaft, arms carried thereby, and blades secured to the arms in twist form and consisting of strips, each having one edge longer than the other, whereby the blade presents the edge of a strap to the material. 95

4. In an agitator, the combination with a structure adapted to turn on an axis, of blades carried thereby and consisting of strips having one edge longer than the other.

5. The combination with a barrel, an agitator within the barrel comprising a central longitudinal shaft, and agitating members carried thereby, a crank for driving said shaft having a removable handle, and means for retaining the handle on the underside of 100 the crank when the crank is secured to the barrel head. 105

6. The combination with a barrel for paints and the like, of an agitator within the barrel for agitating the paints therein, said 110 agitator comprising a central longitudinal shaft, agitating members carried and rotated by said shaft, a crank for engaging the upper end of said shaft, a removable handle for the crank, the crank being recessed on its underside for the reception of the removable handle, and means for securing the crank to the barrel so as to retain the handle beneath the crank, for the purpose specified. 115

7. The combination with a barrel for 120 paints and the like, of an agitator within the barrel, the said agitator having a shaft extending longitudinally through the barrel and into an opening at the center of the top head of the barrel, members secured to said shaft 125 for agitating the paint in the barrel as the shaft is rotated, a crank having a socket portion adapted to engage over the upper end of the shaft for driving the latter, said socket portion extending into the opening in the top 130

- barrel head, a bushing or packing surrounding the said socketed portion of the crank, and a removable handle adapted to be secured to the outer end of the crank, the 5 crank having a recessed under side into which the said handle may be placed when the barrel is prepared for shipment, and means for securing the crank to the barrel so as to hold the handle in position.
- 10 8. The combination with a barrel for paints and the like, of an agitator within the barrel for stirring the paints therein, said agitator comprising a central longitudinal shaft, radial arms secured to said shaft, 15 blades secured to the outer ends of said arms, a crank for engaging the upper end of said shaft, a removable handle for the crank, said crank being recessed on its under side for the reception of the removable handle, and 20 means for securing the crank to the barrel so as to retain the handle beneath the crank, for the purpose specified.
9. The combination with a barrel for paints and the like, of an agitator within the 25 barrel, the said agitator having a shaft extending longitudinally through the barrel and into an opening at the center of the top head of the barrel, cross arms secured to said shaft, blades secured to the outer ends of said 30 cross arms for agitating the paint in the barrel as the shaft is rotated, a crank having a socket portion adapted to engage over the upper end of the shaft for driving the latter, said socketed portion extending into the 35 opening in the top barrel head, a bushing or packing surrounding said socketed portion of the crank, and a removable handle adapted to be secured to the outer end of the crank, the crank having a recessed under side into 40 which the said handle may be placed when the barrel is prepared for shipment or storage, and means for securing the crank to the barrel so as to hold the handle in the said recess.
- 45 10. The combination, with a barrel for paints and the like, of an agitator for the material within the barrel, said agitator comprising a shaft mounted within the barrel, blades supported by said shaft and mounted 50 so as to present one edge of the said blades to the material to be mixed as the shaft is turned, and means for turning said shaft.
11. The combination, with a barrel for paints and the like, of an agitator within said barrel, said agitator comprising a shaft, 55 blades supported by said shaft for agitating the material within the barrel, said blades being arranged to always present an edge to the material to be agitated, said blades being also formed so as to raise and stir the material with which it comes in contact, and means for turning said shaft.
12. The combination, with a barrel, of an agitator therein, said agitator consisting of a central longitudinal shaft, a crank for turning said shaft, radial arms secured to the shaft so as to turn therewith, blades secured to the outer ends of said radial arms and to the shaft, said blades being so mounted as to present an edge to the material within the 70 lower part of the barrel when the shaft is rotated.
13. The combination, with a barrel, of an agitator therefor having a longitudinal shaft, a crank provided with a boss journaled in 75 the head of the barrel adapted to receive the shaft.
14. The combination with a barrel, of an agitator therein having a shaft located substantially axially of the barrel, a substantially aligned opening in the barrel head, a crank having a boss occupying such opening, such boss having a socket to receive the upper end of the shaft, the upper end of the socket being closed and said crank having 85 an annular flange above the head whereby the crank hub forms a closure for the said opening.
15. The combination with a barrel, of an agitator therein, said agitator consisting of 90 a shaft extending centrally and longitudinally in the barrel, a journal for one end of the shaft secured to one head of the barrel, the other end of the shaft extending adjacent to and opening in the other head, and a 95 crank provided with a boss journaled in such opening, said boss having a bore to receive said shaft.

In testimony whereof, I hereunto affix my signature in the presence of two witnesses. 100
